His Attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

TURBINE ELEMENT AND METHOD OF MAKING THE SAME.

Application filed March 30, 1923. Serial No. 628,928.

To all whom it may concern:

Be it known that I, CHRISTIAN STEENSTRUP, a citizen of the United States, residing at Schenectady, county of Schenectady, 5 State of New York, have invented certain new and useful Improvements in Turbine Elements and Methods of Making the Same, of which the following is a specification.

An elastic-fluid turbine depends primarily, for its efficiency upon the proper size and shape of the parts which direct or guide the fluid as it flows from the inlet to the exhaust, and particularly in the case of a multistage impulse-turbine upon the nozzles 10 which are carried by the diaphragms and are commonly called stage nozzles. Briefly stated each diaphragm has a large number of nozzle passages which are closely associated so that the fluid issues therefrom in 15 the form of an annular belt or stream. Each passage has two circumferentially-extending walls and two radially-extending walls, commonly called partitions, each partition being common to two passages. The diaphragm structure also comprises a central disk-like member and an outer ring, the 20 ends of the partitions being secured to both parts. The load on these diaphragms due to the fluid pressure thereon is very heavy 25 and for that reason they are usually made of steel castings. When the nozzle partitions are cast-jointed to the disk and ring, trouble is frequently experienced in the casting operation due to failure of the metal 30 to completely fill the mold, to blow holes, imperfect bonding of the partitions, and to casting strains which in some cases are so great as to crack or distort the partitions. In such a construction there is no fusion 35 of the side edges of the partitions with the cast metal support. To securely fasten the partitions it is necessary to provide them with special anchoring means into which the molten metal flows in the casting operation. 40 Further, it is a very difficult matter to finish the circumferentially-extending walls or surfaces of the diaphragm between the partitions owing to the smallness of the space between them and to the peculiar shape of 45 the partitions themselves. In some cases the passages are so small that there is no practical way to finish them and as a result 50

the rough surfaces very seriously affect the efficiency of the nozzles and hence of the machine as a whole.

My invention has for its object to improve the construction of and also the method of making such turbine elements or diaphragms.

For a consideration of what I believe to be novel and my invention, attention is directed to the accompanying description and the claims appended thereto.

In the attached drawing, Fig. 1 is a cross-section of a diaphragm for a steam 60 turbine; Fig. 2 is a partial plan view of the same; Fig. 3 is a partial cross sectional view of a slight modification showing special anchoring means; Fig. 4 is a perspective view showing a modified form of nozzle 65 structure; Figs. 5 and 6 show in section modified forms of diaphragm structures; Fig. 7 is a plan view of a diaphragm which is built up of segmental pieces or sections, 70 and Figs. 8 and 9 are detail views of modified structures.

10 indicates the central member of a cast steel diaphragm for a turbine which is normally subjected to heavy pressure and at times to great changes of pressure and temperature. It is provided with the usual central opening 11 which receives the packing for the wheel shaft. 12 indicates a cast steel outer ring or member. Between the central and outer members are the nozzles 80 13 which serve to direct the steam from one stage of the turbine to the bucket wheel of the adjacent stage. Each nozzle has four walls, two of which extend circumferentially and two radially as best shown in Fig. 90 2. 14 indicates a ring which is employed in the process of manufacturing and is afterwards cut away. It has two concentric shoulders with which the inner and outer members of the diaphragm engage and are 95 held in position thereby. In the ring are two concentric annular slots 15 in which are seated two concentric and properly shaped partitions 16 which form the smooth circumferential walls of each nozzle or nozzle section. The upper edges of these walls or partitions are retained in their proper position with respect to the axis 100 of the diaphragm by a number of short bars

or clamps 17 which are slotted to receive the partitions 16 and are spot-welded or otherwise secured at their ends to the main members of the diaphragm. In the ring-like walls or partitions 16 are formed slots or openings which contain short radial partitions 18 as shown generally in Figs. 2 and 4. The ends of these partitions project through the circular walls to form anchors. 5

10 It will be seen that the nozzle partitions are located in a chamber or container, the bottom of which is formed by the ring 14 and the sides by the outer surface of the central part of the diaphragm and the inner surface 15 of the outer member, the top being open. The annular partitions 16 form the outer and inner walls of the nozzle and being smooth require no further finishing after they are united with the supporting parts. 20

20 In order to unite the nozzle partitions with the inner and outer members of the diaphragm I employ a composite material invented by me and which forms the subject matter of another application filed by me 25 of even date herewith Serial No. 628,926. Briefly stated this material comprises for the present purpose a base of smooth, self-packing metal particles, made of mild steel for example, having spaces between the par- 30 ticles which are capillary in their nature, and a void-filling, fusing or uniting metal such, for example, as boronized copper or copper which has been treated in a hydro- 35 gen furnace to remove the impurities. In the best form of the invention the base material is composed of small steel balls or shot and for simplicity the term "shot" will be employed hereafter. 40

After the parts have been assembled, as shown in Fig. 1, small steel shot are poured into the chambers around the partitions to the desired level, usually to the tops of the inner and outer members of the diaphragm. To facilitate the settling or packing of the 45 shot the structure may be jarred by suitable means such as a pneumatic hammer. On top of the shot in each chamber is placed boronized copper, usually in small pieces, and of sufficient amount when melted to fill 50 the voids between the shot. If there is any excess it may drain out at the bottom through small drains provided for the purpose. The structure is then placed in a closed furnace in which a supply of hydro- 55 gen or other selected gas is constantly maintained. The temperature of the furnace is then raised to a point where the copper melts and fuses the diaphragm members, partitions and shot into a unitary structure, 60 said temperature being below the melting points of the shot. After being properly cooled the diaphragms may be machined in the ordinary manner during which operations the temporary ring 14 and the clamps 65 17 are removed. Since all of the partitions

are finished before being assembled nothing has to be done to them. It follows from this that the accuracy of the nozzle passages is determined by the original set-up of the partitions and that subsequent operations do not affect it. 70

On account of the fact that the inner and outer members are cast separately and are of the simplest design, merely a disk and a ring, the troubles incident to casting operations are practically eliminated. Since the diaphragm while in the hydrogen furnace is well supported from the under side and since the heat to which it is subjected in the fusing operation is not excessive at any time any strains which may exist in the casting have a chance to and do equalize themselves. The diaphragm parts may be rough-turned before the assembling and fusing operations, but the final machine work should be done afterwards. The composite metal has about the strength of mild steel and for that reason is considerably in excess of that of the uniting metal and because of that fact and also because there is a certain amount of alloyage of the copper and steel shot with the diaphragm members and the nozzle partitions it follows that inner and outer members will be well united or bonded and that as a whole the resulting structure is extremely rugged and well adapted for its purpose. 80

One advantageous way to form the annular partitions 16 is to start with thin concentric metal rings which are suitably anchored in the slots of the temporary ring 14, as by spot-welding or calking at a number of places around the circumference. The base ring and partitions are then mounted in a suitable machine, as a boring mill for example, in which the metal forming the partitions is spun to the desired shape. Afterwards the partitions are slotted to receive the radial partitions. It is to be noted that both partitions flare outwardly from the base ring. The purpose of this construction is to form a throat for the steam in which there is a gradual conversion of pressure into velocity, and since the shape largely determines the efficiency of the turbine a very exact relation of parts must be obtained and preserved during the subsequent operations. 105

Diaphragms constructed in accordance with my invention may be made in one piece or, as is usually the practice, in two pieces, with the plane of division between them, corresponding to that of the shaft so as to facilitate the opening of the machine. 110

Fig. 3 shows a slight modification in which either the inner or the outer member of the diaphragm or both are provided with dovetail or equivalent slots 19 to afford additional anchoring means. 125

Fig. 4 illustrates another construction 130

suitable for the nozzle partitions. In this case the temporary ring 14 is provided as before and inserted in the annular slots 15 thereof are short segmental pieces 20 which when assembled form annular members. These pieces may be stamped out of sheet metal with a suitable die and afterwards formed to shape in a forming die. In the stamping operation slots are provided for the radial partitions 18. These latter may be uniform in thickness or they may be thicker at the upper or steam receiving end than at the bottom or discharge end. In this construction it is preferable to calk the partitions 20 into the grooves in the base ring but they can be spot-welded if desired. The radial partitions being held between the circumferential partitions do not require any additional temporary securing means but there is no objection to providing them if desired. The fact that the steel shot will freely run into the surrounding chamber and will not exert any appreciable pressure means that only very light attachments are necessary.

Fig. 5 illustrates another form of diaphragm which is composed chiefly of composite material, in this case steel shot, and a void-filling material, in this case, copper. 30 25 indicates a container made of thin sheet steel which defines generally the shape of the finished structure. Instead of providing a separate grooved ring 14, the bottom wall of the container is grooved to receive the 35 nozzle walls or partitions 16. The upper ends of the partitions are held in place by clamps 17 as before. After the circumferential nozzle walls and partitions are mounted in place the container is filled with steel shot and the necessary amount of void-filling copper. After this is done the whole structure is placed in a hydrogen furnace or one containing another selected gas and the whole fused in a solid mass. Fig. 6 40 shows a similar construction with the exception that instead of using steel shot only as the base material larger pieces of steel 26 form part of the filling and which are later fused with the shot. These pieces may be 45 in the form of bars and large enough to form reinforcing means for the diaphragm. In machining these diaphragms either the whole of the container may be machined off or only those portions which are necessary 50 to complete the same.

Fig. 7 shows still another form of the invention as applied to a diaphragm wherein a solid center member 10 is provided and the outer member is composed of segmental pieces 27 which are formed separately. They may be formed by the usual methods or by the fusion method previously described. However they are formed they are placed 55 around the center member in the manner shown with chambers or spaces 28 between

adjacent sections as shown in plan in Fig. 7 and in elevation in Fig. 8. After being assembled on a suitable support, the segments are temporarily united by a number of short pieces 29 which may be spot-welded or otherwise secured to said sections. Opposite each piece 29 and on the inside of the nozzle between two adjacent radial partitions are thin temporary pieces of material 30 preferably but not necessarily non-metallic, the function of these temporary pieces is to hold the parts together and to assist in forming chambers and prevent the steel shot from running into the nozzle space. The joints at the inner part of the nozzle are similarly 70 provided with pieces 31 for the same reason, the peripheral surface of the disk 10 forming the inner wall of the chambers. After being thus assembled steel shot are poured into the chambers at the joints; and the necessary 75 void-filling copper added at the proper points. After this the whole structure is placed in a hydrogen furnace and the parts united by the fusion of metal. It is also to be noted that the composite material which 80 is located between the inner parts of the nozzle not only unites the sections but also by reason of the fusion tie or unite the nozzle as a whole to the disk or center member. By using sufficient copper the inner parts of 85 the nozzle will be fused to said disk along their entire surface.

Fig. 9 shows a slightly different form of diaphragm in which the inner or center member 10 is made solid as before and the outer member is composed wholly of my composite material except for the thin wall container and the nozzle partitions. In this case a thin steel band 32 is provided to define the periphery of the diaphragm and also the outer wall of the shot-receiving chamber. The bottom of the chamber is or may be 95 formed of heat-resisting material such as a slab of asbestos 33.

In carrying out my invention it will be 100 observed that the relatively small and delicate parts are formed as a separate structure, which means that they can be formed as accurately as conditions require, and that the relatively massive pieces are also formed 105 separately and that all of said parts or pieces are united into an integral whole by composite material. Due to the nature of said material it does not exert any pressure 110 on the delicate parts during the manufacturing operation and hence the accuracy of said parts is in no way disturbed and further, that since they are accurately formed to shape and size, no additional machine work or finishing thereof is required. It 115 follows from this that a substantial saving 120 is effected.

Instead of making the nozzles as an integral part of their support they may be 125 formed separately and afterwards bolted or 130

- otherwise secured to their support. Such nozzles having the built-up arrangement of the walls may be used for the high pressure end of the turbine.
5. What I claim as new and desire to secure by Letters Patent of the United States, is,—
1. In a turbine element, the combination of thin metal members separately built up 10 to form fluid-directing means with a composite metal support therefor comprising a base of self-packing metal particles and a metal of lower melting point than the base which fills the voids in said base and intimately 15 unites the particles and the directing means, the strength of the composite support being greater than that of the uniting metal.
  2. In a turbine element, the combination 20 of separately built up fluid-directing means comprising thin metal parts which define the fluid passage or passages with a composite metal support therefor comprising steel shot and void-filling copper which 25 latter intimately unites the shot and fluid-directing means, the strength of the support being greater than that of the copper.
  3. In a turbine element, the combination 30 of fluid-directing means comprising annular walls which form the circumferential boundaries of the fluid passages, radially-extending partitions which form the other boundaries of the passages, and a composite metal support for said means comprising a 35 base material of self-packing metal particles and a metal of lower melting point than the base material which fills the voids in the said base material and intimately unites the same with the said fluid-directing means, 40 said composite support having a greater strength than the uniting metal.
  4. In a turbine element, the combination 45 of fluid-directing means comprising a structure built up of sheet metal parts, the walls of said parts forming the guiding surfaces for the fluid, and a carrier therefor of composite material which backs up and supports the parts comprising a mass of self-packing metal particles having voids of a 50 capillary nature between them, and a void-filling metal which has a lower melting point than the particles and which intimately unites said structure and the particles, said composite material having a greater strength 55 than that of the void-filling metal.
  5. In a turbine element, the combination 60 of fluid-directing means comprising a separately built up structure made of sheet metal, the walls of which define the guiding surfaces for the fluid, a supporting member, and a body of composite material for supporting the sheet metal parts and for uniting the same with the member and comprising a mass of self-packing metal 65 particles having voids of a capillary na-
  - ture between them, and a void-filling metal which has a lower melting point than the particles and which unites said particles, structure and member, the strength of the composite material being greater than of 70 the void-filling metal.
  6. In a turbine element, the combination of fluid-directing means comprising a separately built up structure, inner and outer supporting members, and means for uniting said structure with the members which means comprises a body of composite material made up of self-packing metal particles having voids of a capillary nature, and a void-filling metal which has a lower 80 melting point than the particles and which intimately unites the particles with the structure and the members, the composite material having a greater strength than the void-filling metal. 85
  7. In a turbine element, the combination of a fluid-directing means comprising a built up structure, a central disk member, an outer ring member, said structure and members being in spaced relation, and a filling for the spaces between the structure and members comprising steel shot having voids of a capillary nature between them, and a void-filling metal having a lower melting point than the shot, which intimately 90 unites said shot, structure and members, the said filling having a strength greater than that of the void-filling metal. 95
  8. In a turbine structure, the combination of fluid-directing means comprising circular members which form the circumferential walls of said means and radial partitions which are united with the walls at their ends and also divide the space between the walls into passages, a solid support for the 100 means which is spaced therefrom, and a body of composite metal located in said space and comprising metal shot and a metal of lower melting point than the shot which fills the voids between the shot and 110 intimately unites them with said means and the support, said composite metal having approximately the same strength as the metal shot. 105
  9. In a turbine structure, the combination of a nozzle having concentric walls and radial partitions, said walls and partitions defining fluid passages, a carrier therefor, and composite metal for uniting the nozzle and carrier which comprises a 115 base of hard-packed metal particles and an added metal of lower melting point than the base which fills the voids in said base and intimately unites the particles, nozzle and carrier into an integral structure, the said composite metal having a strength substantially greater than that of the added metal. 120
  10. The method of making turbine elements which comprises building up a thin 130

metal structure having spaced side members and partitions which extend across the space between the members, said members and partitions defining fluid-conveying passages, 5 mounting said structure in definite relation to a support, and in spaced relation thereto, filling the space between said structure and the support with self-packing metal particles having voids of a capillary nature between them, adding a metal of lower melting point than the particles in sufficient amount to fill the voids, placing the elements thus formed in a closed furnace in which a supply of selected gas is maintained, and subjecting the same to a temperature sufficiently high to cause the void-filling metal to fuse the said structure and particles together.

11. The method of making turbine elements which comprises assembling thin metal pieces into a structure of the desired size and shape, placing said structure between inner and outer annular supporting members which are separated therefrom by chambers, filling the chambers with metal shot, adding metal to the chamber which has a lower melting point than the shot and in sufficient amount to fill the voids between the shot, placing the element thus formed in a closed furnace in which a supply of selected gas is constantly maintained, and subjecting the same to a temperature sufficiently high to cause the added metal to melt and fuse the metal pieces and the balls into an integral whole.

35 12. The method of making turbine elements which comprises separately forming the inner and outer members, separately

forming the fluid-directing means of thin metal with the walls thereof shaped to define the finished fluid-conveying passages, 40 placing said means in spaced position between the two members, temporarily uniting said members and means to preserve the desired relation of the parts, filling the spaces between the members and means with steel 45 shot, adding copper in sufficient amount to fill the voids between the shot, and placing the element thus assembled in a closed furnace in which a supply of a selected gas is constantly maintained, and subjecting the 50 same to a temperature sufficiently high to cause the copper to fuse the parts into an integral whole.

13. The method of making turbine elements which comprises mounting a pair of contric metal members on a temporary ring, forming said members to the desired shape by a spinning operation, slotting said members, mounting partitions in the slots, surrounding the members with a composite material comprising a base of self-packing metal particles having voids of a capillary nature, adding a void-filling metal which has a lower melting point than the particles, placing the structure thus formed in a closed 65 furnace to which a selected gas is supplied, subjecting the same to a temperature sufficiently high to cause the added metal to melt and fuse the parts together, and removing the temporary ring.

In witness whereof, I have hereunto set my hand this 29th day of March, 1923.

CHRISTIAN STEENSTRUP.
